Inventor
Lawrence Schroder

UNITED STATES PATENT OFFICE.

L. SCHRODER, OF CINCINNATI, OHIO, ASSIGNOR TO JOHN H. SCHRODER & CO., OF SAME PLACE.

LOCK-GUARD.

Specification of Letters Patent No. 24,523, dated June 21, 1859.

To all whom it may concern:

Be it known that I, LAWRENCE SCHRODER, of Cincinnati, in the county of Hamilton and State of Ohio, have invented a new and 5 useful Improvement in Lock-Guards; and I do hereby declare that the following is a full and clear description thereof, reference being had to the accompanying drawings, and the letters of reference marked thereon, 10 making part of this specification.

My invention relates to certain improvements in lock guards intended to be inserted within the locks of doors for the purpose of preventing them from being opened by 15 means of other keys, and at the same time being made adjustable so as to be used in any ordinary lock, as hereinafter set forth.

Figure 1, represents in perspective a section of an ordinary door lock with the lock 20 guard adjusted therein and arranged in the position at which the key of the lock guard may be removed leaving the guard within the lock. (Fig. 2,) is a longitudinal sectional view of the lock guard, showing the 25 internal arrangement of its parts. (Fig. 3) is a plan of the key which forms a part of the lock guard. (Fig. 4) is an elevation of the tumblers.

(a) is a case formed with a longitudinal 30 slot (u), transverse slots (t, t, t) and projection (h).

(d) is a hollow stem made to fit closely within the case (a), the inserted end being formed hollow, so as to receive the tumblers 35 (l, l', l'') and spiral springs (b), and also made with a slot, corresponding with the slot (u) of case (a). The other end of the stem (d) is cast solid, with a recess (d') in its end, and provided with a projecting lip 40 (e) and adjustable sliding collar (c).

(i) is a guide piece, and serves also as a protector for the lip (e).

It is formed with a teat (i') which is inserted in recess (d'), while the other end 45 being screwed firmly to projection (h) secures the guide in its proper position; and holds the stem (d) to its proper place in the case (a).

(l, l', l'') are tumblers, formed with the 50 necks (n) and arranged within the tubular portion of the stem (d) in such manner that the necks (n) will protrude through the slot

of the tubular portion of the stem (d) and slot (u) of the case (a).

(b) are spiral springs arranged in such 55 manner as to sustain the tumblers (l, l', l'') in their proper positions within the stem (d).

(b') is a spiral spring arranged around the stem (d) in such manner as to press 60 against the collar (c) and hold it against the cap (p) of the lock, when the guard is applied to use.

(f) is a key formed with shoulders (m, m', m'') projection (g) and tapering point 65 (m'''). The lock guard is intended to be inserted, in ordinary locks, for the purpose of preventing doors from being opened by means of ordinary keys, skeleton keys, etc., and may be operated as follows, the guard 70 being inserted through the keyhole, into the lock, as represented in Fig. 1): The key (f) being inserted within the guard, the point (m''') presses against the tumbler (l') shoulder (m'') against tumbler (l') and 75 shoulder (m') against tumbler (l') by means of which the springs (b) will be compressed and the tumblers (l, l', l'') moved inwardly, until the shoulder (m) impinges against the case (a), at which time the key 80 will be fully inserted and the necks (n) of the tumblers brought opposite the slots (t), and the projection (g) of the key will have passed within the case (a) and fitted into the slot in the tubular portion of the stem 85 (d), the stem (d) will then be turned by means of the key (f), until the necks (n) of the tumblers are made to bear in the slots (t), by means of which the lip (e) is made to project behind the cap (p) of the lock, 90 and thus secure the guard within the lock, while at the same time the collar (c) is pressed against the outside of the cap (p) of the lock, by means of the spring (b'), and thus the guard is held steady in its place. 95

The key may then be removed from the guard, which is allowed to remain in the lock as a barrier against the insertion of other keys or devices for unlocking doors. By turning the key in a direction opposite to 100 that for locking the guard, the lip (e) is returned within the protector (i, i') and the guard may be withdrawn from the lock with the key.

What I claim as my invention and desire to secure by Letters Patent is—

The arrangement of the several tumblers in combination with intervening springs which vary the spaces between said tumblers and operate the lock in the manner and for the purpose substantially as set forth.

In testimony of which invention I have hereunto set my hand.

LAWRENCE SCHRODER.
